UNITED STATES PATENT OFFICE

VICTOR R. ABRAMS, OF BRUNSWICK, GEORGIA

DEVICE FOR MEASURING, REGULATING, AND METERING SUPPLY OR DISTRIBUTION
OF FLUIDS

Application filed July 1, 1930. Serial No. 465,225.

This invention relates to improvements in devices for measuring, regulating and metering the quantity of fluid which will flow through an orifice upon the application of pressure to the fluid, and the primary object of the invention is to provide such a device as will accurately perform these functions without the use of valves such as are ordinarily used with any measuring piston driven by mechanical means.

A further object is to furnish a device of this character, including a cylinder in which a plurality of pistons operate, the construction being such that at least one of the pistons will positively obstruct the bore of the barrel at all times to absolutely prevent the passage of any fluid through the device without proper functioning of the pistons.

A further object is to provide a device of this kind which is of simple inexpensive and durable construction, and one in which the various elements may be readily assembled or dismantled to facilitate replacement of parts or cleaning of the device.

With the foregoing objects outlined and with other objects in view which will appear as the description proceeds, the invention consists in the novel features hereinafter described in detail, illustrated in the accompanying drawing, and more particularly pointed out in the appended claims.

Referring to the drawing,

Fig. 1 is a longitudinal sectional view of the device illustrated as interposed in a lubricating system, and with the pistons in the positions which they occupy when the structure is ready to be charged.

Fig. 2 is a similar view of the device, but showing the pistons in the positions they assume when the device is charged.

Fig. 3 is a like view, but with the parts in the positions they occupy during the discharge period.

Fig. 4 is an elevation of one end of either piston.

My improved measuring, regulating and metering device may be employed in connection with any fluid, and is particularly useful when employed in a liquid pipe line or the like.

In the drawing, 4 designates a cylinder having a bore 5, preferably of cylindrical shape, which merges at its ends into annular shoulders 6 and 7 that extend outwardly to cylindrical surfaces 8 and 9 that are of larger diameter than the cylindrical surface of the main portion of the bore.

Caps 10 and 11 are connected to the ends of the cylinder by any suitable means such as screw threads 12, and the caps have centrally disposed threaded apertures 13 and 14 which are adapted to be connected to any suitable means, such as pipes 15 and 16 which feed the pressure fluid to and from the device. If the device is employed in a lubricating system, the pipe 15 will convey the lubricant from a suitable pressure source, and the pipe 16 will lead the lubricant from the device to the part or parts to be lubricated.

Stop fingers 17 and 18 project inwardly from the caps and function to halt the pistons 20 and 21, so as to prevent the same from seating snugly against the caps. Each piston has a cylindrical surface 22 which is interrupted by diametrically opposite notches or rabbets 23. The cylindrical surface is of such diameter as to snugly fit the cylindrical bore 5, and each piston is hollowed out to provide an internal socket 25. These sockets are of the same diameter as heads or flanges 26 arranged on the ends of a connecting rod 27. Stop pins 28 project radially through the pistons into close proximity with the rod 27, and the heads 26 are adapted to move between these stop pins and the heads of the pistons.

A coiled spring 29 is arranged in the cylinder and abuts at its ends against the inner ends of the pistons for the purpose of holding the piston 21 away from the piston 20, at a certain time.

A stronger coiled spring 30 is arranged in the cylinder, and has one of its ends abutting against the cap 10, and its other end abutting the piston 20, and when the parts are in normal position, this spring forces the same into the position shown in Fig. 1, and maintains the spring 29 under compression.

The operation of the device is as follows. When a pressure fluid is forced by way of pipe 15 through the opening 14, it will pass

between the head of the piston 21 and the inner surface of the cap 11, and will flow around the stop fingers 18 and into the enlarged portion 9 of the bore of the cylinder. From such place, it will continue to flow through the notches 23, into the space between the two pistons and will then act to force the piston 20 away from the piston 21. This action will continue until the abutment pin 28 of the piston 20 engages the head 26 at the left end of the connecting rod, and while the piston 20 is moving in such manner, the spring 29 will prevent the piston 21 from disengaging the pins 18. As soon, however, as the abutment 28 of the piston 20 strikes the head 26 at that end of the rod, the latter will commence to move with the piston 20, and such movement will continue until the head 26' at the other end of the rod abuts against the pin 28' of the piston 21. As the pressure fluid continues to enter, the pistons will now move toward the left in unison until the parts reach the position shown in Fig. 2. At such time, the two pistons will be closing the ends of the bore 5, and the charge which is arranged in the bore between the pistons, will be an accurately measured one. For the purpose of discharging such charge, the introduction of the pressure fluid is continued, and as it acts against the head of the piston 21, it will cause the latter to exert pressure on the charge, and to force the piston 20 into contact with the stop fingers 17, and as the pressure is continued, the charge will be forced out through the aperture 13, and the parts will assume the position shown in Fig. 3. As soon as the charge has been completely transferred by the device, the pressure on the fluid entering through the aperture 14 is relieved, with the result that the spring 30 moves the pistons toward the right hand end of the cylinder, or back to the position shown in Fig. 1, in which position, the parts will be ready to receive a second charge.

It will be noted that this device employs no valves such as are ordinarily used with measuring pistons driven by mechanical means. Furthermore, there is no time during its operation, when one or the other or both pistons are not in the bore 5. Consequently, there is absolutely no possibility of liquid passing through the device without proper functioning of the pistons, and except for leakage between the pistons and the bore 5, its action is entirely positive and independent of the pressure fluid. In other words, it will deliver the same quantity of liquid at 10 pounds or 100 pounds, or will deliver the same quantity on practically an instantaneous pulsation, as it will supply on a relatively long period motion. This enables the device to be used at locations remote from the fluid pressure, such as the individual bearings of machinery, and other places difficult of access.

I contemplate its application for this purpose, particularly in the lubrication of the chassis of an automobile, also to line shafts, conveyors and other machinery which are inaccessible, but which by means of the invention, may be supplied by a trunk line arranged at a convenient point. 70

The invention will also be used for the measuring of fluids in industrial processes, in the dispensing of carbonated fluids for making carbonated beverages, in the regulation and measuring of syrups, oils and other liquids in the canning, packing and bottling industries. In short, I contemplate employing the device in any environment where it will be applicable. 75

From the foregoing it is believed that the construction, operation and advantages of the invention may be readily understood, and I am aware that changes may be made in the details disclosed, without departing from the spirit of the invention, as expressed in the claims. 80

What is claimed and desired to be secured by Letters Patent is: 90

1. A measuring device including a cylinder having a bore provided with enlarged portions, pistons movably mounted in the bore, and means connecting the pistons and permitting one of the pistons to move relatively to the other, the space between the pistons constituting a measuring chamber, and the pistons being operable under fluid pressure to charge and discharge the measuring chamber. 95

2. In a device of the character described, a cylinder having a bore, connected pistons operating in the bore, the pistons and cylinder being shaped to permit fluid to flow past either one of the pistons while the other piston completely obstructs the bore, the space between the pistons constituting a measuring chamber, and the pistons being operable under fluid pressure to charge and discharge the measuring chamber. 105

3. A device of the character described, including a cylinder, relatively movable connected pistons arranged in the cylinder, the cylinder being shaped to permit fluid to flow past one of the pistons while the other piston completely obstructs the cylinder, the space between the pistons constituting a measuring chamber, and the pistons being operable under fluid pressure to charge and discharge the measuring chamber. 115

4. In a device of the character described, a cylinder having a bore, caps closing the ends of the bore, relatively movable connected pistons arranged in the bore, the bore being shaped to permit fluid in the bore to flow past one of the pistons and to be obstructed by the other piston, the space between the pistons constituting a measuring chamber, and the pistons being operable under 125

fluid pressure to charge and discharge the measuring chamber.

constituting a measuring chamber, and the pistons being operable under fluid pressure to charge and discharge the measuring chamber.

5. In a device of the character described, a cylinder having a bore, apertured caps closing the ends of the bore, and relatively movable connected pistons arranged in the bore, the bore being shaped to permit fluid to flow in the bore past one of the pistons, while the other piston completely closes the bore, the space between the pistons constituting a measuring chamber, and the pistons being operable under fluid pressure to charge and discharge the measuring chamber.

10. In a device of the character described, 70

15 6. In a device of the character described, a cylinder having a bore, apertured caps closing the ends of the bore, and relatively movable connected pistons arranged in the bore, the bore being shaped to permit fluid to flow in the bore past one of the pistons, 20 while the other piston completley closes the bore, and means for preventing the pistons from snugly seating against either one of said caps, the space between the pistons constituting a measuring chamber, and the 25 pistons being operable under fluid pressure to charge and discharge the measuring chamber.

a cylinder having a bore, apertured caps closing the ends of the bore, relatively movable connected pistons arranged within the bore, and each being of the same diameter as the main portion of the bore, the bore having enlargements at its end portions to allow fluid to flow around the pistons when they occupy such portions, and a spring arranged between the pistons and acting to force one piston away from the other, the space between the pistons constituting a measuring chamber, and the pistons being operable under fluid pressure to charge and discharge the measuring chamber.

7. In a device of the character described, a cylinder having a bore, apertured caps 30 closing the ends of the bore, relatively movable connected pistons arranged within the bore, and each being of the same diameter as the main portion of the bore, the bore having enlargements at its end portions to allow 35 fluid to flow around the pistons when they occupy such portions the space between the pistons constituting a measuring chamber, and the pistons being operable under fluid pressure to charge and discharge the measuring chamber.

11. In a device of the character described, a cylinder having a bore provided with enlarged end portions, caps closing the ends of the bore, means to admit fluid into one end of the bore, means for discharging the fluid from the other end of the bore, pistons arranged in the bore, each piston having a portion of the same diameter as the main portion of the bore, means connecting the pistons and permitting the same to move relatively to one another, a spring arranged between the pistons and adapted to hold one piston away from the other, and another spring arranged between one of the caps and one of the pistons, the last mentioned spring being stronger than the first mentioned spring and functioning to normally compress the first mentioned spring and to force both pistons toward one end of the bore. 90 95 100

40 ing chamber.

8. In a device of the character described, a cylinder having a bore, apertured caps closing the ends of the bore, relatively movable connected pistons arranged within the bore, 45 and each being of the same diameter as the main portion of the bore, the bore having enlargements at its end portions to allow fluid to flow around the pistons when they occupy such portions, and means for normally urging the pistons toward one of said caps, the space between the pistons constituting a measuring chamber, and the pistons being operable under fluid pressure to charge and discharge the measuring chamber.

12. In a device of the character described, a cylinder having a bore provided with enlarged end portions, caps closing the ends of the bore, means to admit fluid into one end of the bore, means for discharging the fluid from the other end of the bore, pistons arranged in the bore, each piston having a portion of the same diameter as the main portion of the bore, means connecting the pistons and permitting the same to move relatively to one another, a spring arranged between the pistons and adapted to hold one piston away from the other, and another spring arranged between one of the caps and one of the pistons, the last mentioned spring being stronger than the first mentioned spring and functioning to normally compress the first mentioned spring and to force both pistons toward one end of the bore, each piston having a shoulder which an end of the first mentioned spring abuts.

55 9. In a device of the character described, a cylinder having a bore, apertured caps closing the ends of the bore, relatively movable connected pistons arranged within the bore, and each being of the same diameter, c9 as the main portion of the bore, the bore having enlargements at its end portions to allow fluid to flow around the pistons when they occupy such portions, and a spring in the bore for forcing both pistons toward one of said caps, the space between the pistons

13. In a device of the character described, a cylinder having a bore provided with enlarged end portions, caps closing the ends of the bore, means to admit fluid into one end of the bore, means for discharging the fluid from the other end of the bore, pistons 130

arranged in the bore, each piston having a portion of the same diameter as the main portion of the bore, means connecting the pistons and permitting the same to move relatively to one another, a spring arranged between the pistons and adapted to hold one piston away from the other, and another spring arranged between one of the caps and one of the pistons, the last mentioned spring being stronger than the first mentioned spring and functioning to normally compress the first mentioned spring and to force both pistons toward one end of the bore, said connecting means comprising a rod having heads which slide in the pistons.

14. In a device of the character described, a cylinder having a bore provided with enlarged end portions, caps detachably connected to the ends of the cylinder and provided with inlet and outlet apertures, a pair of pistons arranged in the bore, a rod having its ends connected to the pistons, the rod being movable relatively to the pistons and each piston being movable relatively to the other, a coiled spring bearing at one end against one of said caps and at its opposite end against one of the pistons for normally forcing the pistons toward the other cap so that one of the pistons will normally occupy one of the enlarged portions of the bore, and another coiled spring arranged between the pistons and functioning under certain conditions to prevent one piston from moving while the other is moving away from that piston.

In testimony whereof I affix my signature.
VICTOR R. ABRAMS.
